BEIRNE GORDON, JR., OF UTICA, NEW YORK.

PROTECTING DEVICE FOR COTTON-SPINNING MACHINES.

1,141,457.

Specification of Letters Patent.

Patented June 1, 1915.

Application filed December 16, 1914. Serial No. 877,615.

To all whom it may concern:

Be it known that I, BEIRNE GORDON, Jr., of Utica, in the county of Oneida and State of New York, have invented certain new and useful Improvements in Protecting Devices for Cotton-Spinning Machines; and I do hereby declare that the following is a full, clear, and exact description thereof, which will enable others skilled in the art to which it appertains to make and use the same, reference being had to the accompanying drawings, and to the reference numerals marked thereon, which form part of this specification.

15 My present invention is a protecting device for cotton spinning machines.

In the ordinary cotton spinning machine or spinning mule the threads of cotton or yarn come from the drawing rollers to the spindles mounted upon a carriage alternately moving from and toward the rollers, and successive lengths of the threads are alternately drawn out and twisted by the very rapid rotation of the spindles while 20 the carriage moves from the drawing rollers, and then the lengths of twisted cotton are wound onto the cops upon the relatively slowly rotating spindles while the carriage moves back toward the drawing rollers 25 winding up onto the cops the length that has just been drawn and twisted. During the drawing, twisting or spinning operation proper the threads pass over the counter-faller wire or guide positioned above the spindles so that the cotton will be twisted by the action of the spindles and not wound up thereon upon the cops in process of making upon the spindles. But during the 30 winding operation the faller wire or guide passes downwardly and then upwardly beside the cops so as to guide the threads of cotton on to their respective cops. The result of these operations is that cops or cigar-shaped rolls of spun cotton are gradually 35 formed upon the spindles. These cops at all stages of their formation have cone-shaped tops upon which are wound successive layers of cotton until the cops reach the proper height. This gradual building up- 40 ward of the cops from the bottom results in the bottom portion of the cop being entirely completed before the upper portion, so that the outer threads upon the lower portion of the cop are exposed to the air for a long 45 time before the cop is completed. The pe-

riod during which the outer threads of the cops are thus exposed during the forming of the cops varies under different conditions, such as difference in gage or quality of the cotton, but in most cases may be anywhere 50 from two to four and sometimes six hours. It is found that this long exposure of the lower portion of the cop during the spinning operation causes the outer threads to become dirty, dark or smoky. This dirt or 55 other foreign substance must be absorbed from the air since the cops are not handled by the operatives and do not come in contact with any part of the machine. Furthermore, I have found that the cotton thus 60 exposed upon the cops during the spinning operation becomes dirtier than does the cotton upon cops standing still in the same room for a similar space of time, and also becomes dirtier than does the cotton upon 65 cops left upon the carriage so as to be subjected to the back and forth movement of said carriage, but disconnected from the mechanism of the carriage so as not to have the rapid rotating movement incident 70 to spinning. From these facts, I concluded that the excessively rapid absorption of dirt or other foreign matter by the exposed cotton from the air during the spinning operation was due in some way to the very rapid 75 rotation of the cops during the twisting or spinning operation proper, at which time the rotation of the spindles is usually several thousand times a minute. My theory is that this rapid rotation of the cops produces in 80 some way air currents which draw toward the cops any dirt or other foreign matter that may be floating in the air near the machine, and the dirt thus attracted to the cotton adheres thereto, resulting in the surface 85 of the cotton becoming gradually darker as their formation progresses. The dirt thus settling upon the cotton at this stage of its manufacture cannot be removed, nor the cotton cleansed therefrom, but is permanently 90 injured for many ordinary purposes and for most fine work, and altogether has a greatly depreciated value. The dirt or foreign substance here referred to is not so much the readily discernible street dirt or 95 dirt from a manufacturing quarter which may be kept from the spinning room with ordinary care, but is more particularly the very fine black or dark dirt or matter, such as is suspended in the air on a smoky day, 100

110

which foreign matter cannot be excluded from the spinning room by any ordinary or practical means.

The purpose of my invention is to provide means to prevent the outer threads of the cops of cotton becoming thus soiled or dirty in the course of their manufacture, and the accomplishing of this purpose by the providing of protectors or shields about the cops. These protectors are so arranged and of such extent as to cut off the current of air directly toward or against the sides of the cops and I find that the presence of these protectors along both sides of the row of cops upon the spinning mule very effectively prevents the cops from becoming dirty or darkened as hereinabove mentioned.

On account of the recurring downward and upward movement of the faller wire or guides during the winding operation, it is obvious that a protector cannot be permanently located closely to the receiving side of the row of cops, as such a protector would be in the way of said guides or of the threads going from said guides to the cops.

It is, therefore, a further purpose of my invention to provide a protector along the receiving side of the row of cops on a spinning mule so mounted and connected as to be positioned closely beside the cops during their rapid rotation, that is, during the spinning operation, and so as to be withdrawn therefrom during the winding operation so as not to interfere with the winding operation.

It is a further purpose of my invention to provide means whereby said movable protector on the receiving side of the cops will automatically move away from its protecting or operative position during the winding operation and will return thereto at the close of said winding operation or at the commencement of the spinning operation.

As effective and simple means for so operating the said protector I provide means whereby the protector tends to move away from operative or protecting position, and means connected to the faller wire or guide or other part of the machine whereby the protector is raised while the faller guide is in raised position incident to the spinning operation proper, and is allowed to move from operative position upon the descent of said faller guide incident to the winding operation.

It is a further purpose of my invention to provide a protector along the side of the row of cops opposite to the receiving side of the cops or parallel to the hereinbefore described intermittently moving protector, and in connection with this second protector it is one of the objects of my invention to so mount the said second protector that it may be readily moved away from the cops for convenience in the doffing or loading or

unloading of the spinning mule. It will be understood that this second protector will be normally in the operative or protective position during all the time that the spinning machine is being operated, since the protector upon that side is not in the way of any part of the machine during the operating of the machine and might be permanently fixed on said movable fixture to the carriage were it not for the convenience of moving it away from operative position during the doffing or loading and unloading of the machine.

The drawing is a vertical sectional view taken transversely of the carriage of a cotton spinning machine or spinning mule embodying my invention with the parts shown in full lines in the position they occupy during the drawing and twisting or the spinning operation, and with the parts shown in dotted lines in the position they occupy during the winding operation.

Referring to the drawings in a more particular description, the threads of cotton 3, called yarn and of which for the sake of clearance only one is shown in the drawing, come from the drawing rollers 4 mounted on standards and operated by means well known in the art and not necessary to be shown herein, to their respective spindles 5 which are revolubly mounted in and having their upper ends extending in a slightly inclined direction from above the top of the carriage 6. The carriage 6 is mounted to move back and forth toward and away from the drawing rollers as by having wheels 7 traveling upon tracks 8 and being drawn back and forth by means of a cable 9 connected to said carriage and actuated by any of the usual means (not shown.) Projecting upward from the back or left hand side, as shown in the drawings, of the carriage 6 are brackets 10 at the top of which are mounted rock shafts 11 and 12. From rock shaft 11 extend toward the front of the machine, or the right hand as illustrated in the drawings, sickle-shaped counter-faller brackets 13 supporting the counter-faller wire 14 below the threads of cotton 3 between the row of spindles 5 and the drawing rollers 4 and spaced slightly from the row of spindles 5. The threads of cotton 3 pass over this counter-faller wire or guide 14, which extends the length of the carriage.

From rock shaft 12 extend forwardly of the machine the sickle-shaped faller brackets 15 supporting faller wire or guide 16 between the row of spindles 5 and the counter-faller wire 14 during the spinning operation at a point a little above the level of the tops of the spindles and the counter-faller wire 14. During the drawing and twisting or spinning operation the faller wire 16 and counter-faller wire 14 occupy the position

shown in full lines in the drawing, and the threads of cotton 3 pass over the counter-faller wire 14 and beneath faller wire 16 to the upper part of the spindles 5 by which 5 the cotton is drawn from the drawing rollers and by the very rapid rotation of which the threads of cotton are twisted in the usual well known manner. During this drawing and twisting operation the carriage is moved 10 back from the drawing rollers 4 in the usual way. Upon the carriage 6 completing its backward movement and the drawing and spinning operation having been completed for the lengths of cotton thread drawn out, 15 the carriage 6 commences its forward movement toward the drawing rollers 4 and the counter-faller wire 14 rises to the position shown in dotted lines in the drawing, contacting with the yarn in the usual way and 20 the faller wire or guide 16 passes downwardly in front of the spindles to the position shown in dotted lines in the drawing and upwardly therefrom in order to guide the threads of cotton into proper position 25 upon the cops 18 of cotton formed by the winding up of the cotton upon the spindles 5. These movements of faller wire 16 and counter-faller wire 14 are imparted thereto through their respective brackets, the counter-faller 13 and faller 15 being moved upwardly and downwardly through partial rotation in opposite directions of their respective rock shafts 11 and 12 by means common to this machine (not shown). 30 During the downward and then upward movement of the faller wire 16, the threads of cotton are wound onto the cone-shaped top of the cops 18 by the now relatively slow motion of spindles 5. The spindles 5 are 35 driven by means of the whirls 17 thereon connected by bands 19 to the usual tin drums 20 mounted within the carriage 6. After the carriage has moved back toward the drawing rollers 4 and wound up the spun cotton upon the cops 18, the faller wire 16 returns to its upward position and counter-faller wire 14 returns to its lower position, 40 the carriage begins to move backward and the drawing and spinning operation is again 45 begun with a rapid rotation of spindles 5.

The parts of the spinning mule heretofore briefly described are found without material variation in practically all the common cotton spinning machines. To this machine I 50 add and connect my protecting device, as follows: Upon the back or left hand side 21 of the carriage 6 at its upper corner is secured by means of hinges 22 a normally stationary protector or shield 23 extending 55 along the row of spindles and of a height sufficient to protect the cops to be formed upon the spindles. The protector 23 when in normal position is as close to the cops 60 as practical in order to leave relatively little 65 air space between the protector and the row

of cops. This protector normally holds itself in upright and operative position by reason of being placed parallel to the rows of spindles and, therefore, inclined slightly toward the front of the machine. If the inclination of the spindles on any particular machine is not sufficient to hold the protector in upright position with sufficient certainty various obvious means, such as springs or 70 holders may be provided. This protector on the rear side of the row of spindles normally retains its operative position at all stages of the drawing, spinning and winding operations, since it is not in the way of the threads of cotton being wound upon the cops 75 nor of the faller brackets 15, nor any other part of the machine. However, for convenience in doffing the machine, the protector is not rigidly secured in upright position but movably so mounted as by hinges 80 22 whereby the protector 23 may be swung backward and downward affording ready access to the spindles.

Upon the top 23 in front of the spindles or toward the right, as illustrated in the 90 drawings, is movably mounted another or front protector 24, by means of hinges 25, of proper height to protect the row of cops upon the cotton receiving side thereof and extending the length of the machine and 95 close enough to the cops 18 to protect them from appreciable side currents of air. This protector is adapted to be positioned in upright or protecting position, as indicated in full lines in the drawings substantially 100 parallel to the row of spindles, and is also adapted to be moved upon its hinges to a position withdrawn from the cops or folded back partly toward the top 25 of the carriage 6. On account of its inclination toward the front of the machine, the weight 105 of this protector naturally tends to make the protector fall toward the top, but I prefer to have further yielding means to accomplish this movement in order to have the 110 movement take place with positiveness and certainty. As such means, I attach to this protector 24 one end of a cord 26, which passes forwardly over a roller 27 upon the forward upper corner of the carriage 6 and 115 thence downwardly where it is attached to a weight 28. This weight in an obvious manner tends to withdraw the protector 24 from its operative position to a position folded down toward the top of the carriage. As 120 effective means for raising this protector 24 to operative position and holding it there during the drawing and spinning operation, I provide straps 29 having their lower ends attached to the upper or free edge of the 125 protector 24, and having their upper ends secured to the free end of the faller brackets 15 or to the faller wire or guides 16 secured thereto. The strap is of such length that when the faller bracket 15 or its wire 16 is 130

in the upper position incident to drawing and spinning the cotton, the strap 29 will be pulled up sufficiently to draw the protector 24 to operative position and hold it there. 5 As soon as the winding operation is to begin, the faller bracket 15 and its guide wire 16 moves toward lowered position and at once the protector 24 is released and under the tension of weight 28 moves to withdrawn 10 position allowing the faller brackets 15 and the faller wire or guide 16 to move downwardly without interference and without in any way interfering with the threads of cotton passing beneath the faller wire toward the cops 18. Upon the winding operation being completed, the faller bracket 15 rises carrying with it the intermittently moving protector 24 against the tension of weight 28 so that the protector is again 15 raised to operative position by the time the rapid rotation of the spindles is renewed. This intermittent positioning of the protector upon the receiving side of the cops goes on automatically as long as the spinning machine is in operation. 20 25

It will be seen that I have provided protecting means along both sides of the row of spindles and the cops thereon, which protectors are always in operative position during 30 the rapid rotation of the spindles and cops, and that the rear protector is in position at all times, except when the machine is being doffed, and that the forward protector upon the receiving side of the cops is in operative 35 position during the time when there is need thereof, that is, during the rapid rotation of the cops and is withdrawn from operative position when it would otherwise be in the way of the faller wire guiding the threads 40 of cotton to the cops. While these protectors do not, of course, prevent access of the air to the cops during rapid rotation thereof, they do operate to prevent the action of air currents directly toward the sides of the cops 45 in such a way as to prevent the hereinbefore-mentioned excessively rapid accumulation of dirt or foreign matter upon the outer threads of cotton upon the cops.

It is obvious that various modifications 50 or changes may be made in the form or shape of the protectors or their operative or connecting means without departing from the spirit of my invention.

Rests 32 may be provided upon the top 23 55 of the carriage 6 to support the protector 24 when it has fallen far enough away from the row of cops 18.

If desired to relieve the faller brackets 15 of the work of raising the front protector 60 24 from lowered position, arms 30 may be provided as upon the brackets 31 that supports the drawing rollers 4, of such length and arrangement, that they will engage and force upward the protector 24 as said protector is moved there against when the car-

riage 6 approaches the end of its movement toward the rollers 4. While the protector is so raised the fallen brackets return to upward position and then through strap 29 the protector is easily held up as the carriage 70 moves away from the rollers.

What I claim as new and desire to secure by Letters Patent is:

1. In a cotton spinning machine, the combination of spindles rapidly rotating during the drawing and twisting of the cotton and slowly revolving during the winding thereon of the cotton, a faller guide positioned above the spindles during said rapid rotation and moving down and back beside the spindles during the winding operation, a movable protector on the receiving side of the spindles, and means for positioning said protector beside the spindles during their rapid rotation and for withdrawing it therefrom during the winding operation. 75 80 85

2. In a cotton spinning machine, the combination of spindles rapidly rotating during the drawing and twisting of the cotton and slowly revolving during the winding thereon of the cotton, a faller guide positioned above the spindles during said rapid rotation and moving down and back beside the spindles during the winding operation, a movable protector on the receiving side of the spindles, 90 means for positioning said protector beside the spindles during their rapid rotation and for withdrawing it therefrom during the winding operation and a protector arranged along the other side of the row of spindles. 95 100

3. In a cotton spinning machine, the combination of spindles rapidly rotating during the drawing and twisting of the cotton and slowly revolving during the winding thereon of the cotton, a faller guide positioned above the spindles during said rapid rotation and moving down and back beside the spindles during the winding operation, a movable protector on the receiving side of the spindles, and means operatively connected to said machine for positioning said protector beside the spindles during their rapid rotation and for withdrawing it therefrom during the winding operation. 105 110 115

4. In a cotton spinning machine, the combination of spindles rapidly rotating during the drawing and twisting of the cotton and slowly revolving during the winding thereon of the cotton, a faller guide positioned above the spindles during said rapid rotation and moving down and back beside the spindles during the winding operation, a movable protector on the receiving side of the spindles, means operatively connected to said machine for positioning said protector beside the spindles during their rapid rotation and for withdrawing it therefrom during the winding operation, and a protector arranged along the other side of the row of spindles. 120 125 130
